United States Patent Office

Des. 183,168
Patented July 8, 1958

183,168

DECANTER

William E. Herber, Evanston, Ill.

Application April 27, 1956, Serial No. 41,222

Term of patent 3½ years

(Cl. D58—8)

Fig. 1.

Fig. 4.

Fig. 2.

Fig. 3.

Fig. 1 is a perspective view of a decanter, showing my new design;

Fig. 2 is a side elevational view thereof from the side opposite to that shown in Fig. 1;

Fig. 3 is a top plan view thereof; and

Fig. 4 is a fragmentary sectional detail view taken on line 4—4 of Fig. 3.

I claim:

The ornamental design for a decanter, as shown.
